UNITED STATES PATENT OFFICE.

WILLIAM JAMES LANE AND GEORGE LANE, OF POUGHKEEPSIE, NEW YORK,
ASSIGNORS TO THE LANE MOTOR VEHICLE COMPANY, A CORPORATION
OF NEW JERSEY.

MOTOR-VEHICLE.

SPECIFICATION forming part of Letters Patent No. 690,160, dated December 31, 1901.

Application filed February 25, 1901. Serial No. 48,791. (No model.)

To all whom it may concern:

Be it known that we, WILLIAM JAMES LANE and GEORGE LANE, citizens of the United States, residing at Poughkeepsie, county of 5 Dutchess, State of New York, have invented certain new and useful Improvements in Motor-Vehicles, of which the following is a specification.

Our invention relates to motor-vehicles of 10 the type adapted to be operated by steam.

Our invention consists in a special construction of the running-gear for motor-vehicles, whereby the frame is materially strengthened and greater flexibility obtained both in 15 the frame and between the frame and the body of the vehicle upon which the motor device is secured.

Our invention further consists in various 20 details of construction of the frame, the vehicle-body, the arrangement of the motor device relative to the body and the running-gear, and the means for adjusting the motor device relative to the running-gear and to the steering mechanism of the vehicle, all of which 25 will be set forth in the specification and specifically pointed out in the claims.

The object of our invention is to construct 30 a motor-vehicle which will be suitable for use over country roads and which will require little care and attention on the part of the operator.

The accompanying drawings will serve to illustrate our invention, in which—

Figure 1 is a side elevation. Fig. 2 is a 35 bottom plan view. Fig. 3 is a front elevation with a portion of the carriage-body in section and a portion of the boiler broken away to show the location of the air-tank. Fig. 4 is a rear elevation and section through the water-tank. Fig. 5 is an enlarged side elevation 40 of the device for adjusting the motor relative to the rear axle.

Our invention is shown in the accompanying 45 drawings as embodied in a two-seated vehicle adapted to carry four persons. We wish it understood, however, that we do not limit ourselves to the employment of a vehicle of the type described, as our various improvements in running-gear and attachments for 50 motor-vehicles may be embodied and used in

various types of motor-vehicles and similar apparatus.

In the drawings, 10 indicates the supporting-frame as a whole; 11, the body of the vehicle; 12, the boiler, located under the front seat; 13, a burner situated under the boiler; 14, a water-tank located under the rear seat; 15, a steam-engine suspended below the body of the vehicle; 16, compensating gear on rear axle; 17, a sprocket-chain passing over 60 sprocket on compensating gear on rear axle and sprocket of engine 15; 18, a device for adjusting the motor relative to the rear axle; 19, a fuel-supply tank; 20, an air-tank; 21, a starting-lever, and 22 a reversing-lever. 65

The body of the vehicle, whatever its form, is elastically supported on the frame 10, the general features of construction of which are best shown in Fig. 2. The frame is tubular and consists of the support for the front axle 70 23, the support for the rear axle 24, the reach 25, and the transverse brace 26. The support for the front axle is provided with the bifurcated ends 27, Fig. 3, in which are pivoted the separate axles 28 of the forward wheels 75 29. The support for the rear axle is formed as a tube 24 and carries the rear axle and is turned at its center toward the front of the vehicle to form the rectangular portion 24^a, which occupies the same horizontal plane as 80 the tube 24. The rectangular portion 24^a is connected to the reach-tubes 25 through the transverse brace 26, and the reach-tubes 25 are pivoted at 25^a to the support 23 for the front axles. 85

30 indicates the rear axle. The rear axle is carried in the tube 24, but is bare at the opening of the rectangular portion 24^a. Upon that portion of the axle 30 which is not included in the tube 24 is mounted the compensating sprocket-wheel 31 and band-wheel 32. 90

By reason of the peculiar construction of the support for the rear axle great strength is given to the frame. There is also provided a convenient point of support for one end of 95 the compensating device 18 and for the operating-lever 33 of the band-brake 34, which is thrown into and out of operation through the rod 35, connected to the foot-lever 36 on the forward part of the vehicle. 100

- In order to take up the slack due to the wear of the sprocket-chain 17, as also to compensate for the vertical movement of the sprocket-wheel of the engine relative to the sprocket-wheel on the rear axle, we introduce between the engine-frame and the transverse brace 26 a compensating device 18. The compensating device consists of the extensible rods 37, connected at one end to the engine 5 and at the other end provided with the forked extensions 38, Fig. 5, each fork carrying a transverse pin 39. The pins 39 have their bearings in the cavities 40 of the sectors 41, which are mounted upon the transverse brace 26. As the body of the vehicle moves upon its springs vertically the pins 39 alternately find their bearings in the cavities 40 of the sectors 41, and by this means the sprocket-chain 17 is kept taut.
- 10 The guiding of the carriage is accomplished by means of the lever 42, which is pivoted to the inclined rod 43, carried in the bearings 44, secured to the body of the vehicle. The inclined rod is bent at right angles backward 15 and pivotally connected to the transverse rod 45, which in turn is connected through the levers 46, secured to the end of the vertical portions of the forward axles 28. Movement of the lever 42 to the right or left produces a 20 corresponding transverse movement of the rod 45, and hence a turning movement of the axles 28.

In the foregoing specification we have generally described the construction of the running gear of our improved motor-vehicle. We wish it understood that we do not consider ourselves limited to the exact features of construction shown and described, as it is evident that many changes may be made which will 35 embody the intent of our invention.

Having thus described our invention, we claim—

1. In a motor-vehicle, the combination with the supporting-frame, a vehicle-body, a motor device suspended from and below said body, a sprocket-wheel on the driving-shaft of the motor device, a sprocket-wheel on one axle, a sprocket-chain for connecting the two sprocket-wheels, and a device for adjusting 45 the distance between the sprocket-wheels.
2. In a motor-vehicle, the combination with the supporting-frame, a vehicle-body, a motor device suspended from and below the body and angularly disposed as regards said body, a sprocket-wheel on the driving-shaft 50 of the motor device, a sprocket-wheel on one axle, a sprocket-chain connecting the said sprocket-wheels, and a device for adjusting the distance between the sprocket-wheels.
3. In a motor-vehicle, the combination with the supporting-frame, an elastically-suspended vehicle-body, a motor device pivotally suspended below said body, a sprocket-wheel carried by said motor device, a sprocket-wheel 55 on one axle, a chain connecting the sprocket-wheels, and a device for adjusting the difference between the sprocket-wheels.

4. In a motor-vehicle, the combination with the supporting-frame and the driving mechanism carried by said frame, an elastically-supported vehicle-body, and a pivoted motor supported on and below said body, coaxing with said driving mechanism on said supporting-frame.

5. In a motor-vehicle, the combination with 75 the supporting-frame, an elastically-suspended vehicle-body, a motor device suspended from and below said body, driving mechanism carried on the supporting-frame, and a power-transmission device interposed between said motor device and said driving mechanism.

6. In a motor-vehicle, the combination with the supporting-frame, independent pivoted axles carried by the forward member of said frame, wheels freely revoluble on said axles, a single axle carried within the straight portions of the rear member of said frame, wheels secured to the ends of said axle, a sprocket mounted upon said axle, a vehicle-body, a 90 motor device suspended from and below said vehicle-body, a sprocket-wheel mounted on the driving-shaft of said motor device, and a sprocket-chain connecting said sprocket-wheels.

7. In a motor-vehicle, the combination with the supporting-frame, driving mechanism on said frame, a vehicle-body, a motor device suspended from and below said vehicle-body, and a power-transmission device between said motor device and the driving mechanism on said frame, whereby the power exhibited by the motor will be transmitted in the direction of the longitudinal axis of said vehicle.

8. In a motor-vehicle, the combination with 105 the supporting-frame, driving mechanism on said frame, a vehicle-body, a motor device suspended from and below said vehicle-body, a sprocket-wheel on the driving-shaft of said motor device having its axis of revolution located in a plane parallel to and approximating that of the axis of revolution of the sprocket-wheel on the rear axle, and a flexible power-transmission device interposed between said sprocket-wheels.

9. In a motor-vehicle, the combination with the supporting-frame, driving mechanism thereon, an elastically-suspended vehicle-body, a motor device suspended from and below the body, and a flexible power-transmission device between said motor device and said driving mechanism on frame, whereby the power exerted by the motor device carried by the vehicle-body will be exerted through the driving mechanism on the vehicle-frame in the direction of the longitudinal axis of the frame.

10. In a motor-vehicle, the combination of a supporting-frame, driving mechanism thereon, a vehicle-body, a motor device suspended from and below said body and adapted to exert its power at an angle to said body, and a power-transmission device between said motor device and said driving mechanism,

whereby the power of the angularly-disposed motor will be exhibited through the driving mechanism in a direction corresponding to the longitudinal axis of the vehicle.

5 11. In a motor - vehicle, the combination with a vehicle-body, of a steam-engine suspended from and below the body, said steam-engine arranged at an angle with its cylinders near to the body and its driving-shaft in a 10 plane approximating that occupied by the axis of the driving-axle of said vehicle.

12. In a motor - vehicle, the combination with the running-gear, of an angularly-disposed reciprocating motor device, and power- 15 transmission means between the driving-shaft of motor device and the driving mechanism of the running-gear, whereby the shocks due to the reciprocation of the motor device

will be transmitted at an angle to the vertical axis and the power exhibited by the motor device transmitted along the longitudinal axis of said vehicle. 20

13. In a motor - vehicle, the combination with the running-gear and body, of a water-tank and boiler carried by the body, a steam- 25 engine carried below the body and at an angle to the body, and power-transmission means between the engine and the rear axle of the vehicle.

In testimony whereof we affix our signatures in the presence of two witnesses. 30
